ARITHMETICAL DEVICE FOR WRITING INSTRUMENTS

Jack Weiser, Los Angeles, Calif.

Application June 23, 1952, Serial No. 295,062

4 Claims. (Cl. 235—87)

1

My invention relates generally to writing instruments such as pens and pencils, and more particularly to arithmetical devices as combined therewith.

An object of my invention is to provide an arithmetical device particularly adapted, although not necessarily, for use by children and students in the study of elementary arithmetic, and which in its association with a writing instrument enables the answers to problems in the various elementary arithmetic processes to be directly read with the utmost ease and dispatch following a simple and quick adjustment of the device, all to the end of expediting the mathematical education of the user by providing a convenient and entertaining method of obtaining the answers to a wide range of arithmetic problems.

Another object of my invention is to provide an arithmetical device for writing instruments of the above described character which is of simple, compact and inexpensive construction enabling the device to be embodied in a pen or pencil at a slight additional cost.

With these and other objects in view, my invention resides in the combinations, arrangements and functional relationships of elements as set forth in the following specification and particularly pointed out in the appended claims.

In the accompanying drawings,

Figure 1 is a view of a writing instrument in side elevation, partly in section, with one form of arithmetical device embodying my invention applied thereto, and showing one position of adjustment of the device;

Figure 2 is a view similar to Figure 1 and showing another position of adjustment of the device;

Figure 3 is a view in side elevation showing the body of the writing instrument with the casing and number sheet of the device removed;

Figure 4 is an enlarged longitudinal axial sectional view of the writing instrument;

Figures 5 and 6 are transverse sectional views taken respectively on the lines 5—5 and 6—6 of Figure 4; and

Figure 7 is a plan view of a typical number sheet embodied in my invention.

Referring specifically to the drawings, my invention is shown for the purpose of illustration combined with a writing instrument such as a ball pen which comprises a body B and a cap C therefor constructed of plastic, metal or other suitable material. The body B is composed of one element in the form of an open-ended cylin-

2

drical barrel or tube 10 externally screw threaded at one end as shown at 11 (Figure 4) to removably receive internal screw threads 12 of a tapered neck 13.

5 A conventional ball pen unit U having the usual writing ball 14 at its tip end 15 and an ink supply tube 16 is removably fitted in the neck by means of an enlarged intermediate screw threaded portion 17 which screws into a threaded bore 18 in the neck, so as to rigidly support the ball pen unit U with the ball 14 protruding slightly from the neck and the tube 16 projecting coaxially into the barrel 10.

For the major portion of its length the barrel 10 is slightly reduced in diameter as indicated at 19 to receive a number sheet S which is wrapped around the barrel and is permanently fixed thereto by a suitable adhesive. Mounted 15 for rotation and axial adjustment on the barrel 10 so as to bear only on the full diameter thereof beyond the ends of the number sheet S is the other element of the body B in the form of a cylindrical casing or tube 20, one end of which closes the corresponding end of the barrel.

20 As shown in Figures 1 and 2, the casing 20 is provided adjacent to its left hand end with a single control opening or window 21. Between the opening 21 and the right hand end of the casing, same is provided with a row of openings 22 uniformly spaced apart and consecutively numbered 1, 2, 3, 4, 5, 6, 7, 8, 9, 10, 11 and 12 so as to have these definite values for co-action with the control opening 21 in a manner to be later described.

25 Adjacent to the neck 13 and covered by the casing 20 are spaced annular grooves 25 and 26. The grooves 25 and 26 are connected at one point only by a groove 27 extending longitudinally of the barrel so as to provide communication between the grooves 25 and 26 for an internal projection 28 in the form of a pin or teat on the inside of the casing.

The projection 28 is adapted to travel in the groove 25 or 26 upon rotation of the casing on 30 the barrel and according as the casing is adjusted longitudinally on the barrel to occupy either the extreme position shown in Figure 1 or the extreme position shown in Figures 2 and 4. It will thus be clear that the casing 20 is permanently mounted on the barrel 10 by the projection 28 and the grooves 25, 26 and 27, for rotational adjustment in either of two selected positions of axial adjustment.

In the present instance the number sheet S 35 is provided with rows of numerals extending

circumferentially and longitudinally of the barrel. The relationships and values of the number tables on the sheet are such that the answers to problems in addition and subtraction can be directly read by use of the control opening 21 and the numbered openings 22 with the casing 20 axially adjusted on the barrel 10 to the position shown in Figure 2, whereas the answers to problems in multiplication and division can be directly read by the use of these openings with the casing 20 adjusted axially on the barrel to the position shown in Figure 1.

For this purpose alternate circumferential rows 30 of numbers on the sheet S which constitute one table, may be printed in black, whereas the other alternate rows 31 of numbers on the sheet which constitute a second table, may be printed in red. The numbers of these two tables will appear in the openings 22 according as the casing is axially adjusted on the barrel 20 to one or the other of the extreme positions shown in Figures 1 and 2.

Two circumferential rows 32 and 33 of control numbers are arranged at the left hand end of the aforesaid tables and are printed in black and red, respectively, for co-action with the table of the same color, and are arranged to appear in the control opening 21 according as numbers of the table of corresponding color appear in the openings 22.

To indicate the necessary axial setting of the casing 20 for one type of problem or another, plus and minus signs are associated with the legend "Black" and a direction indicating arrow for problems in additions and subtraction, whereas multiplication and division signs are associated with the legend "Red" and a direction indicating arrow for problems in multiplication and division, all of which is suitably scribed or imprinted on the casing as shown in Figures 1 and 2.

In operation, let it be assumed that the casing 20 has been axially adjusted to the position shown in Figure 2 for the reading of answers to problems in addition and subtraction which utilize the black printed table and control numbers of the number sheet. For example, to add 3 to 9, the barrel 10 is rotated until the number 3 appears in the opening 21 as shown in Figure 2. The sum 12 of 3 and 9 can be read directly in that one of the openings 22 having the indicated value of 9.

To subtract 3 from 12, the process is reversed by merely reading as the answer the indicated value 9 of the opening 22 in which the number 12 appears.

For the reading of answers to problems in multiplication and division, the barrel 10 is rotated until the projection 28 is aligned with the groove 27 which may be when the series of numbers 1 to 12 of either the black or red table appear in the openings 22. The casing 23 may now be adjusted axially on the barrel to the position shown in Figure 1. For example, to multiply 5 and 8, the barrel is now rotated until the number 5 appears in the control opening 21. The product 40 can now be read directly in that one of the openings 22 having the indicated value of 8.

To divide 40 by 5, this process is reversed by merely reading as the answer the indicated value 8 of the opening 22 in which the number 40 appears.

From the foregoing description it will be evident that other problems such as square root

and cube root can be answered with equal ease and dispatch by the use of different tables on the number sheet S, and that a greater range can be obtained by enlarged tables.

Furthermore it will be manifest that by a simple relative axial adjustment of the barrel and casing, one table or another on the sheet S may be utilized in conjunction with the openings 21 and 22 so as to provide for a maximum range of problems and answers consistent with the compactness of a writing instrument such as a pen or pencil.

It will be understood that if desired, a suitable magnifier 35 (Figure 4) may be applied to the casing 20 so as to magnify much smaller print on the tables to an easily readable size and thus permit the range of the tables to be greatly increased in the small space provided on the barrel 10.

I claim:

1. In an instrument of the class described, an arithmetical device comprising: a barrel having thereon a plurality of arithmetic tables each composed of circumferentially extending rows of numbers, with the rows of one table alternating with the rows of the other table along the length of the barrel; said barrel having rows of circumferentially extending control numbers, one row for each of said tables; a casing having a series of openings with accompanying indicia designating predetermined number values for said openings; said casing having a control opening; means mounting and confining said casing on said barrel in any one of a plurality of longitudinally spaced positions for relative rotation; and means co-acting with the last means to enable relative translational adjustment of said casing and barrel from one to another of said positions to be effected in a predetermined position of relative rotational adjustment of the casing and barrel to accordingly dispose the numbers of one table or another for viewing in said series of openings and the numbers of one or another of said rows of control numbers for viewing in said control opening upon relative rotational adjustment of the casing and barrel.

2. In an instrument of the class described, an arithmetical device comprising: a barrel having thereon a plurality of arithmetic tables each composed of circumferentially extending rows of numbers, with the rows of one table alternating with the rows of another table along the length of the barrel; said barrel having rows of circumferentially extending control numbers, one row for each of said tables; a casing having a series of openings with accompanying indicia designating predetermined number values for said openings; said casing having a control opening; said barrel having a plurality of annular grooves one for each of said tables and spaced apart along the length of the barrel, and a transfer groove connecting said annular grooves; said casing having a projection working in said annular grooves and passable through said transfer groove from one annular groove to another to accordingly dispose the numbers of one table or another for viewing in said series of openings, and the numbers of one or another of said rows of control numbers for viewing in said control opening upon relative rotational adjustment of the casing and barrel.

3. In an instrument of the class described, two elements arranged in telescoped relation; the inner one of said elements having a plurality of arithmetic tables each composed of circumfer-

entially extending rows of numbers, with the rows of one table alternating with the rows of the other table along the length of such element; said inner element having rows of circumferentially extending control numbers one row for each of said tables; the outer one of said elements having a series of openings with accompanying indicia designating predetermined number values for said openings; said outer element having a control opening; means operatively connecting and confining said elements in any one of a plurality of longitudinally spaced positions for relative rotary adjustment; and means co-acting with the last means to enable relative longitudinal adjustment of said elements from any one of said positions to another to be effected in a predetermined position of relative rotational adjustment of the elements to accordingly dispose the numbers of one table or the other for viewing in said series of openings, and the numbers of one or the other of said rows of control numbers for viewing in said control opening upon relative rotational adjustment of said elements.

4. In an instrument of the class described, two elements arranged in telescoped relation; the inner one of said elements having a plurality of arithmetic tables each composed of circumferentially extending rows of numbers, with the rows of one table alternating with the rows of the other table along the length of such element; said inner element having rows of circumferentially extending control numbers one row for each of said tables; the outer one of said elements having a series of openings with accom- 30
